(57) **CLAIM**

The ornamental design for a decorated blanket, as shown and described.

DESCRIPTION

FIG. 1 is a perspective view of the decorated blanket showing our new design;

FIG. 2 is a front view of the blanket shown in FIG. 1;

FIG. 3 is a rear view thereof;

FIG. 4 is a left side view of FIG. 1;

FIG. 5 is a right side view of FIG. 1;

FIG. 6 is a top view of FIG. 1; and,

FIG. 7 is a bottom view thereof.

The parallel curved broken lines form the bounds of the claim and also form no part of the claim.
